DESIGN.

A. J. D. OHM.

ELECTRIC LAMP.

APPLICATION FILED JAN. 30, 1920.

55,430.

Patented June 8, 1920.

Albert J. D. Ohm
Inventor
By his Attorney
Mac G. O'Dowd, Esq.

UNITED STATES PATENT OFFICE.

ALBERT J. D. OHM, OF ASTORIA, NEW YORK, ASSIGNOR TO LION ELECTRIC APPLIANCE CO., OF BROOKLYN, NEW YORK.

DESIGN FOR AN ELECTRIC LAMP.

55,430.

Specification for Design.

Patented June 8, 1920.

Application filed January 30, 1920. Serial No. 355,178. Term of patent 3½ years.

To all whom it may concern:

Be it known that I, ALBERT J. D. OHM, a citizen of the United States of America, residing at Astoria, county of Queens, and State of New York, have invented a new, original, and ornamental Design for Electric Lamps, of which the following is a specification, reference being had to the accompanying drawing forming part thereof.

The figure is an elevation of the lamp showing my design.

I claim:

The ornamental design for an electric lamp as shown.

ALBERT J. D. OHM.

Witnesses:

MAX D. ORDMANN,
JOSEPH T. McMAHON.
